CLAIM

The ornamental design for a calibrated (ruled) adhesive-type tape, as shown and described.

DESCRIPTION

FIG. 1 is a perspective view of a portion of a calibrated (ruled) adhesive-type tape, illustrating English and metric calibrations, showing my new design;

FIG. 2 is a partial front elevational view of the invention, illustrating serrations at a first 24 inch (61 centimeter) mark;

FIG. 3 is a partial front elevational view of the invention, illustrating serrations at a second 24 inch mark;

FIG. 4 is a partial rear elevational view of the invention;

FIG. 5 is a left-side elevational view of the invention;

FIG. 6 is a right-side elevational view of the invention; and,

FIG. 7 is a top plan view of the invention, the bottom plan view being a mirror image thereof.

FIGS. 1, 2, 3, 4 and 7 illustrate a repeating portion of the tape of the invention, as torn from a roll of tape (or the like), not shown.
